UNITED STATES PATENT OFFICE.

GEORGE H. REYNOLDS, OF NEW YORK, N. Y., ASSIGNOR OF TWO-THIRDS
TO CORNELIUS H. DELAMATER AND GEORGE H. ROBINSON, OF SAME
PLACE.

PRESS.

SPECIFICATION forming part of Letters Patent No. 244,672, dated July 19, 1881.

Application filed June 22, 1881. (Model.)

To all whom it may concern:

Be it known that I, GEORGE H. REYNOLDS, of the city and State of New York, have invented certain new and useful Improvements 5 in Presses for Pressing and Baling Cotton and other Substances, of which the following is a full, clear, and exact description, reference being had to the accompanying drawings forming part of this specification.

10 This invention relates to presses for pressing or pressing and baling cotton and other substances, in which either an elastic fluid, as steam, or inelastic fluid, as water, is employed as the compressing agent, and the power is a progressive one by reason of variation in leverage of the mechanical means used to transmit the force of said agent to the platen, and in which a compound bed or platen is used, the same comprising a pressing-plate which is adjustable independently of the platen, and hydraulic devices or means for varying the distances apart of the pressing-surfaces independently of the platen, to make available the full effect of the leverage under varying thicknesses of bales or packages.

15 It will suffice here to describe steam as the power used to work the platen of the press, and said press as being employed for pressing and baling cotton, and having its platen or follower arranged to effect the compression in an upward direction; but such action may be reversed or the press be arranged to work in a horizontal or other direction instead of vertically.

20 The means employed to transmit the working-power of the press to the platen with a progressive effect, by reason of an increasing leverage, will here be described as consisting of a steam-piston, racks on the rod of said piston, rocking toothed sectors, with which said racks engage, and rods connecting said sectors with the platen; but no claim is here made to such means.

25 The invention consists in certain combinations of means whereby not only the pressure may be equalized on bales or packages of unequal bulk or capacity, but a straight action for the platen is obtained, regardless of difference in the hardness or compactness of the

two ends of the bale or package under compression; and, without having recourse to special mechanism for the purpose, the adjustable pressing-plate is made to always stop in one place when forced outward or down to its extreme limit, and caused to occupy a fixed 50 convenient position for introducing the bale or package to the press.

30 In the accompanying drawings, Figure 1 represents a side elevation of a press suitable for pressing and baling cotton, constructed in accordance with my invention. Fig. 2 is a horizontal section of the same on the line *xx*; Fig. 3, a horizontal section, upon a larger scale, through certain hydraulic cylinders connected with the pressing-bed or stationary resistance-plate, and pipes and valves for controlling the ingress and egress of water or other liquid to and from said cylinders for the purpose of regulating the position of an adjustable pressing-plate applied to said bed; and Fig. 4 is a vertical section of the same in part.

35 A is the main frame, which may be of any suitable construction, and B a pressing-bed or stationary resistance-plate secured at any desired height from the ground to said frame, 75 and having mounted on it a steam-cylinder, C, by or through which power is transmitted to the moving resistance plate or platen D, which is here shown as arranged below the bed or stationary resistance-plate B. The power is 40 transmitted from the cylinder C to the platen D, to effect the necessary compressing action, by or through the upward movement of a piston within the cylinder C, controlled by the admission of the steam to the lower end of 85 said cylinder. The platen, however, is not directly connected with said piston, but indirectly, in order that the press may have an increasing power or action throughout the compressing-stroke of the platen by means of intervening 90 devices having a varying leverage, as in other progressive power-presses. Thus the rod E of the piston in the cylinder C is arranged to pass out through the upper end of said cylinder, and is furnished with racks *b b* on opposite sides of it. These racks gear with toothed sectors G G, arranged within the upper portion of the main frame, on opposite sides of it,

and are provided with shafts or bearings *c c*, on or by which they are free to rock.

H H are rods connecting the platen D with the sectors G G at any desired distance from the centers of motion of said sectors, but in such relation thereto that when the platen is fully raised, as shown in Fig. 1, the sectors will exert their most powerful effect by reason of the joint-pins *d*, which attach the rods H to the sectors, approximating a culminating position over the centers or shafts *c* of said sectors, and so that when the platen is fully lowered the sectors, in commencing to raise the platen, will work at their least advantageous leverage, and progressively or gradually become more effective as the joint-pins *d* approach their culminating position over the centers or shafts *c*. This latter position of the parts, or any other given position approximating it, forms the limit to the platen's upper or pressing stroke, and represents a fixed standard of pressure which it is desired to submit each one of a series or any number of cotton or other bales or packages to, regardless of their capacity or bulk of material to be pressed. To this end, and in order that the cotton or other substance as pressed may reach a uniform level to facilitate baling and delivery, regardless of the varying bulk of the bales, which it is difficult or impossible always to equalize, the pressing-bed or stationary resistance-plate B has combined with it one or more hydraulic cylinders, I, having pistons or rams J in them, which pistons or rams are attached to an adjustable pressing-plate, K, arranged beneath the resistance-plate B, and when at rest virtually forming a part of the same. These cylinders I are in communication above the pistons or rams J by pipes L, having check-valves *l* in them, with a tank, M, arranged above the press and containing water or any other suitable inelastic fluid, so that the pressing-plate K, forming part of or connected with the stationary resistance-plate B, is forced outward or downward and held in a given position by said water to allow of the platen D rising under the thinnest bale to be pressed to its maximum height, as hereinbefore referred to.

The adjustable pressing-plate K is guided in its up or down adjustment by working between uprights or guides S S, and is arrested, when fully forced down or out, by stops *m' m'* on said guides, thus providing, without the aid of special mechanism or plungers, for the adjustment of the pressing-plate K clear down to a convenient distance or height for introducing the bale or package to the press. Applied to the water-supply pipe L, however, or to a branch connection between two or more of said pipes, is a valve or cock, N, operative by hand and controlling the egress of the water from the cylinders I back by a return-pipe, O, to the tank M, so that when in the course of pressing bales of different thickness

or capacity it is seen that the bulk under pressure is too great to admit of the maximum pressure and highest position for the platen being reached, the water, by turning the cock N, is allowed to flow back by the pipe O into the tank M, and the pressing-plate K thus adjusted to admit of a uniform maximum compressing result.

Instead of the adjustable pressing-plate K, cylinders I, and rams J being applied to the stationary bed or resistance-plate B, said adjustable pressing-plate, cylinders, and rams may be applied to the moving resistance plate or platen D. In this latter case the pipes which connect the tank with the hydraulic cylinders may either be flexible, or be fitted to slide in stuffing-boxes, to provide for the different distances of said cylinders from the tank consequent on the movement of the platen.

The cock N, which controls the egress of the water from the cylinders I back by the pipe O to the tank M, is here shown as arranged between said cylinders. By this arrangement of said cock the latter not merely serves to control the ingress and egress of water to and from both cylinders, but to separate said cylinders, so that when closed water cannot flow from one cylinder to the other, and consequently, should the bale be harder at one end than the other, will not allow of one end of the platen rising more than the other, so that the bale will be pressed square or regular at both of its ends.

I claim—

1. In a progressive power-press having an adjustable pressing-plate applied to one of its resistance-plates, and two or more hydraulic cylinders having rams which control said pressing-plate, and a tank having supply and return pipes in connection with said hydraulic cylinders, a cock or valve arranged between said cylinders and constructed to control the ingress and egress of the water to and from said cylinders, and to prevent the liquid from passing from one of said cylinders to the other, substantially as and for the purposes specified.

2. The combination, with the pressing-bed or stationary resistance-plate B, and with the adjustable pressing-plate K and its hydraulic rams and cylinders J I, of the guides S for said pressing-plate, and the stops *m' m'*, attached to said guides, essentially as and for the purpose herein set forth.

3. The combination of the check-valves *l* with the liquid-supply pipes L, the tank M, the return-pipe O, the cock or valve N, the hydraulic cylinders I I, the pistons or rams J, the adjustable pressing-plate K, and the stationary bed or resistance-plate B, essentially as and for the purposes herein set forth.
